UNITED STATES PATENT OFFICE.

CHARLES J. BENDER, OF CHICAGO, ILLINOIS.

LEAF-TURNING DEVICE.

1,136,927.

Specification of Letters Patent. Patented Apr. 27, 1915.

Application filed April 20, 1914. Serial No. 833,145.

To all whom it may concern:

Be it known that I, CHARLES J. BENDER, a citizen of the United States, residing at Chicago, in the county of Cook and State of Illinois, have invented certain new and useful Improvements in Leaf-Turning Devices, of which the following is a specification.

This invention relates to devices for turning the pages of sheet music or books by means of a foot-actuated mechanism, thus relieving the performer of the necessity of turning the pages by hand.

The present invention has for its object to provide a simple and efficient device of the kind stated, and to this end it consists in a novel combination and arrangement of parts to be hereinafter described and claimed.

In order that the invention may be better understood, reference is had to the accompanying drawings, in which—

Figure 1 is a vertical section of the front portion of a piano showing the application of the invention, parts being broken away; Fig. 2 is a plan view showing the support of the mechanism, and a closure; Fig. 3 is a view similar to the last preceding showing the closure swung open to expose the leaf-turning devices, one of the leaf-holding parts being shown dotted; Fig. 4 is a section on the line 4—4 of Fig. 3, the sheet supporting device being shown partly broken away; Fig. 5 is a cross-section on the line 5—5 of Fig. 2; Fig. 6 is a horizontal section on the line 6—6 of Fig. 5, and Fig. 7 is a perspective view of one of the leaf-turning units.

Referring specifically to the drawings, 10 denotes the music shelf of a piano which serves to support the leaf-turning mechanism. The shelf carries a depending spindle 11 on which is mounted to swing in a horizontal plane, a series of arms 12 having hub portions 13 through which the spindle passes. These arms carry blocks 14 at their outer ends to which are attached thin metal strips 15 extending horizontally and having two upstanding pairs of leaf-engaging fingers 16 between which the music sheet or leaf is adapted to be placed. Connection between the strips and the blocks is made by downward extensions 17 on the former which are fitted into slits made in the top of the blocks and have tenons 18 which fit in mortises in the bottom of the slits. Thus the strips are fastened to the blocks and are prevented from rotating therein.

To place the device ready for operation

the arms 12 are swung around to locate the blocks 14 to one side of the axis 11 of the arms, which locates the strips 15 correspondingly as shown dotted in Fig. 3. The music sheets are placed between the fingers 16. Upon swinging the arms to bring the same to the opposite side of their axis, the strips are carried in the same direction, and the sheets engaged by the fingers are thus turned or swung over, said strips turning bodily about an axis corresponding to the axis of the arms. The sheets are held by the fingers in two places to assure their being turned when the strips swing as stated.

The arms 12 are of different lengths, and their outer ends are offset to bring the blocks in a compact group at the starting point and at the end of their forward swing. The blocks are also so arranged in the group that they may swing in proper consecutive order without interfering with each other, and the strips 15 are correspondingly arranged.

The means for swinging the arms 12 to actuate the sheet-turning members 15 comprises a longitudinally slidable bar 19 supported by the shelf 10 having a series of rack teeth 20 arranged in stepped relation or at different levels. From each hub 13 extends a pair of teeth 21. The hubs 13 being superposed on the spindle 11, it will be evident that the teeth lie in different horizontal planes, and they correspond to the stepped arrangement of the rack teeth 20. Thus, when the bar 19 is actuated, the highest set of teeth 20 engages the teeth 21 of the uppermost arm 12 and swings the same. When the bar is again advanced, the next set of teeth engages the teeth of the second arm from the top, and so on until all the arms have been swung over to turn the leaves. The arm next to the top one is connected to the first page or sheet, the next one below to the second sheet and so on throughout the series. Upon reversing the movement of the bar 19, the arms swing back in reverse order.

The bar 19 is actuated by a pinion 22 in mesh with a rack 23 on the back edge of the bar. The pinion 22 is in mesh with a pinion 24 fast on the upper end of a vertical shaft 25 having at its lower end a bevel gear 26 which is in mesh with a similar gear 27 on a short shaft 28 carrying a crank disk or other suitable actuating device 29, which latter is located near the bottom of the front wall 30 of the piano casing so as to be read-

ily accessible to the feet of the performer. The shaft and the gears are located inside the casing of the piano as shown in Fig. 1, and the front wall thereof has a bearing 31 for the lower end of the shaft, the upper end of the shaft being supported by a suitable bracket 32 which also has a support for the shaft 33 of the pinion 22. The shaft 28 is supported by the wall 30.

10 In the shelf 10 is an arcuate opening 34 to accommodate the parts carried by the arms 12, the same swinging in said opening. In order to close this opening when the device is not in use, a slide 35 is provided, the 15 same being curved to conform to the curvature of the opening. This slide may be connected to the uppermost one of the arms 12 so that when said arm is actuated, the slide swings to uncover the opening. The strips 20 15 are then attached and the pages or leaves to be turned are connected thereto, after which the device is ready for operation.

Before the slide 35 can be closed the strips 15 carrying the fingers 16 must be removed 25 from the blocks 14 of the arms 12.

I claim:

1. A leaf-turning device comprising a support, a spindle carried by the support, a series of swinging arms mounted in super- 30 posed relation on the spindle, said arms having hubs through which the spindle passes,

and the hubs having teeth, means for connecting the arms to the leaves to be turned, the support having an arcuate opening in which said means swing, a longitudinally 35 slidable bar having teeth which are arranged in stepped relation to correspond to the position of the teeth of the hubs, means for actuating said bar, a slide for covering the aforesaid opening, and a connection between the uppermost arm and the slide for actuating the latter to uncover the opening.

2. A leaf-turning device comprising a support, a spindle carried by the support, a series of swinging arms mounted in super- 45 posed relation on the spindle, said arms having hubs through which the spindle passes, and the hubs having teeth, blocks mounted on the outer ends of the arms, sheet supporting strips carried by the blocks 50 and having sheet-engaging fingers, a longitudinally slidable bar having teeth which are arranged in stepped relation to correspond to the position of the teeth of the hubs, and means for actuating said bar. 55

In testimony whereof I affix my signature in presence of two witnesses.

CHARLES J. BENDER.
